(57) CLAIM

The ornamental design for a miniature connector with molded boot having two shoulders, as shown and described.

DESCRIPTION

FIG. 1 is a perspective view of the miniature connector with molded boot having two shoulders according to the present invention.

FIG. 2 is a top view of the miniature connector with molded boot having two shoulders shown in FIG. 1.

FIG. 3 is a bottom view of the miniature connector with molded boot having two shoulders shown in FIG. 1.

FIG. 4 is a side view of the miniature connector with molded boot having two shoulders shown in FIG. 1.

FIG. 5 is a side view of the miniature connector with molded boot having two shoulders shown in FIG. 1.

FIG. 6 is a front view of the miniature connector with molded boot having two shoulders shown in FIG. 1; and, FIG. 7 is a rear view of the miniature connector with molded boot having two shoulders shown in FIG. 1.

The broken lines throughout the drawing figures are included for the purpose of illustrating environmental structure only and form no part of the claimed design.
